US0D1037063S

(12) **United States Design Patent** (10) **Patent No.:** **US D1,037,063 S**
(45) **Date of Patent:** **** Jul. 30, 2024**

(54) **LINKING MEMBER FOR WEARABLE STRAP**

(71) Applicant: **Whoop, Inc.**, Boston, MA (US)

(72) Inventors: **Aurelian Nicolae**, Providence, RI (US); **Benjamin August Rothenberg Peterson**, Cambridge, MA (US); **Anahis Araxy Kechejian**, Arlington, MA (US); **Johan Liden**, Brooklyn, NY (US); **Brett Tobias Tom**, Richmond, CA (US); **Nick Burrows**, Brooklyn, NY (US); **Eliot Avery Reshetar-Jost**, Austin, TX (US); **William Ahmed**, Boston, MA (US)

(73) Assignee: **Whoop, Inc.**, Boston, MA (US)

(**) Term: **15 Years**

(21) Appl. No.: **29/925,412**

(22) Filed: **Jan. 24, 2024**

Related U.S. Application Data

(63) Continuation of application No. 29/794,715, filed on Jun. 15, 2021, now Pat. No. Des. 1,018,350.

(57) **CLAIM**

The ornamental design for a linking member for wearable strap, as shown and described.

DESCRIPTION

FIG. 1 is a top perspective view of a design for a linking member for a wearable strap;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view thereof engaged with an unclaimed strap;

FIG. 9 is a right side perspective view thereof engaged with an unclaimed strap;

FIG. 10 is a top-front perspective view thereof partially engaged with an unclaimed device; and,

FIG. 11 is a top-front perspective view thereof fully engaged with an unclaimed device.

The broken lines illustrate environmental structure and form no part of the claimed design.

1 Claim, 8 Drawing Sheets
